UNITED STATES PATENT OFFICE.

EMORY GLENN SIMPSON, OF DETROIT, MICHIGAN, ASSIGNOR TO FISHER BODY CORPORATION, OF DETROIT, MICHIGAN, A CORPORATION OF NEW YORK.

DOOR LOCK.

Application filed April 28, 1920. Serial No. 377,173.

To all whom it may concern:

Be it known that I, EMORY GLENN SIMPSON, a citizen of the United States, residing at Detroit, in the county of Wayne and 5 State of Michigan, have invented certain new and useful Improvements in Door Locks, of which the following is a specification.

This invention relates to door locks and 10 has for its object an automobile door lock provided with a locking arrangement controlled either from the outside by a cylinder or pin lock key, or from the inside by a button to hold the outside bolt actuator 15 against movement. This locking is effected without interfering with the inside actuating lever which is still free to move.

The lock cylinder is placed at a point removed from the locking device and hence 20 the movement has to be transferred from one remote point to another, which is effected by the special devices that I have designed.

In a previous application (Serial No. 353,218) I have described and claimed a 25 locking device for locking the outside actuator but this is controlled solely by the key for the cylinder or pin lock or solely by a button. The construction that I am now about to describe can be controlled either by 30 the cylinder or pin lock or by a button on the inside of the door, and consequently has advantages and features not possessed by the construction described in my previous application.

35 In the drawings,—

Fig. 1 is an elevation of the lock taken from the inside of the lock.

Fig. 2 is a section on the line 2—2 of Fig. 1.

40 Fig. 3 is a perspective showing the member that transmits the movement from the cylinder or pin lock cylinder to the locking dog.

Fig. 4 is a detail of the crank member on 45 the end of the lock spindle.

Fig. 5 is a vertical cross section of the lock applied to a door.

Fig. 6 is a section on the line 6—6 of Fig. 5.

50 Fig. 7 is a fragmentary inside elevation of a lock showing the outside bolt actuator in the course of operation.

The lock casing is designated *a* and includes a front plate and rear plate *b* and 55 which is secured by screws, lugs, etc., to the

front plate to guide the sliding bolt *c*, whose movement is resisted by the spring *d*. *e* represents the inside or actuator lever; *f* the outside actuator. These two actuators engage the lugs *g* and *h* respectively on the 60 sliding bolt *c* so as to retract the same when the actuator is given the proper turning movement. This much of the construction is old lock construction. In my previous application I have shown a locking dog *j* 65 that may be controlled by the barrel of the cylinder or pin lock, or in a modified form I have shown a button on the inside of the door for controlling this locking dog. In the present application this locking dog is 70 controlled by both the barrel of the cylinder or pin lock and by the button on the inside of the door.

i designates a channelled guide riveted to the outside of the lock casing in which is 75 guided a draft bar *k* provided with a pair of projecting lugs *l*, one of which is adapted to be engaged by the finger *m* on the crank member *n* that is secured to the end of the spindle *o* in alignment with the barrel *p* 80 of the cylinder or pin lock.

As is well known, the key can be withdrawn from the cylinder or pin lock in only one position. In the position of the parts shown in Fig. 1, if one desires to disengage 85 the locking dog *j* from the path of the outside actuator *f*, this may be done either by turning the button *s* on the inside of the door to turn the dog *j* out of interfering position with the actuator *f*, or by turning the 90 cylinder or pin key to turn the crank member *n* counter-clockwise, as viewed in Fig. 1, through a complete turn. When the dog *j* is turned clockwise through about an eighth of a turn by means of the button *s*, this 95 will raise the draft bar *k* and also turn the crank member *n* through an eighth of a turn. However, this will in no way affect the barrel of the cylinder or pin lock because a lost motion connection is provided between them, 100 as is clearly shown in Fig. 6, giving a lost motion of 45 degrees. The pin *q* through the cylinder or pin lock barrel and the segmental groove *r* in the spindle *o* serve to provide the lost motion. When the key is 105 used to turn the locking dog it will have to be turned in one direction to engage the dog with the actuator and in the opposite direction to disengage the same, the amount of turning and the movement to release the key 110

110

being dependent upon whether the button or the key has previously been used to operate the locking dog. The locking dog is riveted to the lock casing, *a*, tightly enough so that it remains in any position to which it is set.

What I claim is:

1. In a lock, the combination of a sliding bolt, an outside actuator, a locking dog engaging the same, a cylinder lock provided with connections with the locking dog to actuate the same and provided with lost motion within the connections themselves and including a remote draft connection with the locking dog, and a button on the inside of the door for actuating the locking dog.
2. In a lock, the combination of a sliding bolt, an outside actuator therefor, a locking dog for engaging in or out of the path of the actuator, a sliding bar engaging with the locking dog and connecting with a point below the actuator, a locking mechanism located at such point below the outside actuator and having lost motion connection with the said draft bar, and a button on the inside of the door for actuating the dog without interference from the said lock due to the lost motion connection.
3. In a lock, the combination of a sliding bolt, an outside actuator therefor, a locking dog adapted to be swung in or out of the path of the actuator, a draft bar engaging with the dog and connecting with a point below the outside actuator, and a locking mechanism located at such point below the outside actuator and having an operative connection with said draft bar.
4. In a lock, the combination of a lock housing, a sliding bolt therein, an outside actuator, a locking dog adapted to swing in or out of the path of the outside actuator, a guide secured to the lock housing, a draft bar slidably secured in the guide and having connections with the locking dog, and a locking mechanism located below the outside actuator and having connection with the lower end of said draft bar.
5. In a lock, the combination of a sliding bolt, an outside actuator therefor, a locking dog adapted to swing in or out of the path of the actuator, a button on the inside of the door for operating the dog, and a locking mechanism on the outside of the door for operating the dog and provided with a lost motion connection with the dog including a spindle having a segmental groove, and a lock barrel having a pin adapted to engage in the segmental groove.
6. In a latch the combination with a latch bolt, of a lever handle operating the same, a spindle cam also adapted to operate the latch bolt, a pivotal dog adapted to be moved into the path of and against said cam, a

slide connected with said dog and a lock mechanism adapted to lift said slide and move said dog out of the path of the said cam.

7. In a vehicle door lock, the combination of a casing, a sliding bolt guided therein, an inside-operated bolt retractor, an outside-operated bolt retractor, a locking dog for dogging said outside-operated retractor, but permitting the bolt to slide and the inside-operated retractor to be operated, a pin-tumbler-locking mechanism for retracting the dog from the dogging position, and accessible with a key from the outside of the door, and a member on the inside of the door for operating the dog, the said latter member operable upon the dog without exerting turning effort on the pin tumbler lock cylinder.

8. In a vehicle door lock, the combination of a casing, a sliding bolt guided therein, an outside-operated bolt retractor, an inside-operated bolt retractor independent of the first mentioned retractor, a locking dog for dogging the outside-operated retractor but permitting the bolt to slide and the inside retractor be operated, a locking mechanism accessible with a key from the outside of the door for moving the dog from the dogging position, and a thumb member on the inside of the door for moving the dog into the dogging position, the said locking mechanism and the said thumb member being located on opposite sides of the sliding bolt and being provided with connections for permitting operation of the dog from a relatively remote position.

9. In a vehicle door lock, the combination of a casing, a sliding bolt guided therein, an outside-operated bolt retractor, an independent inside-operated bolt retractor, a locking dog for dogging the outside-operated bolt retractor, but permitting the bolt to slide and the inside-operated retractor to be operated, a pin tumbler locking mechanism accessible with a key from the outside of the door for removing the dog from the dogging position and having connections with the portion of the dog that is effective against the outside-operated bolt retractor, which permits the location of the key hole at a point relatively remote on the lock from the location of the working portion of said dog, and a thumb member on the inside of the door for moving the dog into the dogging position, the said thumb member and the said locking mechanism being so arranged and connected that operation of the thumb member does not affect the locking mechanism while operation of the lock turns said thumb member.

In testimony whereof I affix my signature.

EMORY GLENN SIMPSON.
